PRODUCTION OF DIOLEFINS

Wilson D. Seyfried, Wooster, Tex., assignor to
 Standard Oil Development Company, a cor-
 poration of Delaware

Application May 18, 1944, Serial No. 536,209

6 Claims. (Cl. 260—680)

1

The present invention is directed to a process for treating hydrocarbons to recover therefrom a fraction rich in unsaturated compounds of the character of diolefins. In its more specific aspects, it is directed to a process wherein an olefin containing hydrocarbon feed stock is dehydrogenated to form diolefins and in which the manipulative steps prevent the formation of peroxides in the hydrocarbon stream.

A process commonly used in the art for producing diolefins of the character of butadiene includes the steps of subjecting a predominantly olefinic feed stock to dehydrogenation conditions in a dehydrogenation reactor to form diolefins as well as other unsaturated materials, such as acetylenes. The hydrocarbon stream from the dehydrogenation unit is quenched by being brought into intimate contact with a quench oil, and after this quenching step it is further cooled to condense a diolefin-containing fraction which is removed to a suitable stabilization zone. The step in the process of contacting the hydrocarbon fraction removed from the dehydrogenation reactor with a quench oil is essential for profitable commercial operations in order to terminate the reaction and prevent the conversion of diolefins into less desirable materials. The quenching step is necessarily carried out at relatively high temperatures, and if free oxygen is allowed to enter the quenching zone it will react with the unsaturated materials present therein to form peroxides. Such peroxides are to be avoided because they not only are easily detonated, but in addition they catalyze the formation of high molecular weight polymers from the unsaturated hydrocarbons, such as diolefins and acetylenes, present in the hydrocarbon stream.

The product removed from the dehydrogenation zone does not have free oxygen present therein so the quenching zone may be operated without free oxygen being present therein by the selection of a suitable quenching oil. In accordance with the present invention, free oxygen is removed from the quenching oil by the addition of a suitable antioxidant inhibitor to the quenching oil. It is usually desirable to supplement the addition of antioxidant inhibitors to the quenching oil with the storage of oil under a blanket of inert gas and when such a storage method is used, the inhibitor serves initially to remove oxygen from the quenching oil and is also available in the oil in case the storage system allows oxygen-containing gases to come in contact with the oil after it has been initially treated.

The oxidation inhibitor to be employed may be

any of the commonly known oxidation inhibitors which are soluble in petroleum. A suitable inhibitor is isobutyl-p-amino phenol. This inhibitor may be employed in amounts varying from about 0.05 to 0.50 lb. per 1,000 gals. of petroleum. Greater amounts may be employed, but are not required. Amounts that render the cost undesirably high are not attractive for the additional reason that they are ineffective. Other inhibitors of the phenolic or amino type may be employed. A particularly suitable class of inhibitors are those which are known in the art as gum inhibitors in motor fuels. A preferred type of inhibitor is a cut of petroleum phenols obtained by extracting heavy cracked distillates boiling in the range of about 250°-700° F. with 30°-50° Baumé sodium hydroxide solution and acidifying the extract to release the phenols. These petroleum phenols are effective in quantities as low as 0.25 lb./1,000 gals. of petroleum fraction.

A preferred embodiment of the present invention will now be described in conjunction with the drawing, in which the sole figure is in the form of a diagrammatic flow sheet.

Turning now specifically to the drawing, an olefin-containing feed stock is passed via inlet 11 into dehydrogenation reactor 12, maintained under suitable conditions to cause the conversion of substantial amounts of olefins in the feed stock to diolefins. In addition to the resulting diolefins, minor amounts of acetylenes are also formed in the dehydrogenation reactor. Hot hydrocarbon product is removed from vessel 12 by line 13, having cooler 14 present therein. The vapors removed from cooler 14 are still at a relatively high temperature and will cause the conversion of the desirable diolefins into undesirable materials if the temperature thereof is not reduced rapidly, and for this reason the vapors are discharged from line 13 into vessel 15, which serves as a quenching zone. A heavy quenching oil containing an antioxidant inhibitor is introduced into the upper portion of tower 15 by inlet 16 and flows downwardly through the tower countercurrent to the hot hydrocarbon vapors therein. The contacting of the hot vapors with the quenching oil should be under such conditions that the temperature of the hot vapors is reduced several hundred degrees F. in a very short interval of time. This quenching must be sufficient to reduce the temperature of the vapor below that at which substantial conversion of the diolefins into other products will take place. The quenched vapors are withdrawn from tower 15 through line 17 and

subjected to cooling steps to cause cooling and condensation of the desired diolefin-containing product. In the drawing the hot vapors pass through line 17 into cooler 18 of the heat exchanger type and pass thence through line 19 into tower 20, where they are quenched by contact with water. Quenching water accumulating in the lower portion of the tower is recycled through line 21 containing pump 22 and cooling means 23 and returned into the upper portion of the tower. The hot vapors flow upwardly through tower 20 countercurrent to the flow of the water therein and are removed from the upper portion of the tower through line 24 and passed into a suitable means, such as drum 25, to separate entrained water from the hydrocarbon vapors. Separated water is removed from the lower portion of the drum through outlet 26. Hydrocarbon vapors are withdrawn from the upper portion of the drum through outlet 27 and are passed through compressor 28, cooler 29 and into a second drum 30. The compression and cooling steps to which the vapors are subjected causes the condensation of the major portion of the diolefin fraction. This desired fraction settles out in drum 30 and may be removed from the drum through outlet 31 and sent to a suitable stabilizing means, not shown. The uncondensed hydrocarbons in vessel 30 may have present therein minor portions of desirable diolefins, and are passed from drum 30 through line 32 to absorber vessel 33. A heavy oil is introduced into an upper portion of tower 33 by line 34 and flows downwardly therein to dissolve diolefins and other hydrocarbons from the upwardly flowing vapor. The absorption oil with the desired constituents dissolved therein may be removed from the lower portion of the tower via line 35 and hydrocarbon gases and vapors are removed from the top of the tower by line 36 and discarded from the system.

High boiling oil suitable for use in the quenching zone 15 is introduced via inlet 40 and as it flows through this line a small amount of antioxidant inhibitor is added thereto by line 41. The oil containing the inhibitor is discharged into storage tank 45. If desired, the surface of the oil in storage tank 45 may be allowed to come in contact with the atmosphere and the inhibitor in the oil relied upon to prevent the presence of free oxygen in the oil. Under such conditions, it is necessary to add additional antioxidant inhibitor from time to time to replace the inhibitor which is being continuously used up by coming in contact with the oxygen of the atmosphere. In the preferred operation, however, the initially inhibited oil is passed into storage tank 45 and thereupon blanketed with an oxygen-free gas. A suitable inert gas for this purpose is methane but other oxygen-free gases, such as flue gas or nitrogen, may also be used for this purpose. The inert gas may be stored in vessel 46 and removed therefrom to the upper portion of tank 45 by line 47 controlled by valve 48. As oil is needed for the quenching tower it is withdrawn from the tank through line 49 controlled by valve 50 and allowed to enter tower 15 via inlet 16.

The quenching oil accumulated at the bottom of tower 15 has dissolved therein small amounts of the hydrocarbon vapors. This accumulated quench oil is withdrawn from the tower through line 51 containing pump 52 and the stream split, with a portion being returned to the tower by line 53 and the remainder being passed through line 54 to a stripping tower 55 provided with heating means 56. Vapors separated from the quenching

oil in stripping tower 55 are returned to quenching tower 15 through line 57. The stripped quenching oil resulting from the stripping action in tower 55 is withdrawn from the bottom of the tower through line 58, passed through a cooler 59 and is then used as the lean absorbent oil in absorption tower 33. The rich absorption oil removed from tower 33 via line 35 is admixed with the oil flowing in line 53 and the mixture returned to quenching tower 15.

As a specific example of the preparation of a quench oil, a Coastal gas oil having an initial boiling point of 590° F., a final boiling point of 720° F., a viscosity at 100° F. of 77.9 Saybolt seconds, and a gravity of 25.7° A. P. I., had added thereto isobutyl-p-amino phenol as an inhibitor in amounts of 0.25 pound of inhibitor per 1000 gallons of oil. This inhibited oil was then stored under a blanket of methane in a storage tank and a quench oil was withdrawn therefrom as desired for quenching the hot vapors removed from a dehydrogenation reactor. The substitution of this inhibited quench oil with no free oxygen present therein for the quench oil previously employed resulted in a substantial reduction in the polymers formed in the hydrocarbon stream and reduced substantially the fouling of the equipment. As another specific example, a raffinate having an initial boiling point of 590° F. and a final boiling point of 720° F. and inhibited in the same manner has been employed as a quench oil with similar satisfactory results.

The temperatures of the dehydrogenation reaction and the suitable quenching range for reducing the temperatures of the gaseous product removed from the dehydrogenation reactor are well known to the art and are described, for example, in detail in U. S. patent application Serial No. 510,204, filed in the name of Carl E. Kleiber et al. on November 13, 1943, now Patent No. 2,414,817. As a typical example, it may be stated that the hydrocarbon vapors removed from the dehydrogenation reactor may have a temperature in the range of 1150° to 1300° F., that the cooler 14, which may conveniently be a waste heat boiler, may serve to reduce the temperature of the hydrocarbon vapors to a temperature ranging from 500° F. to 600° F., and the quenching step conducted in vessel 15 may be operated to reduce the temperature of the vaporous hydrocarbons to within the range of 200° F. to 250° F. It is to be understood that these conditions are given by way of example only, and are not intended as limitation of the process.

Having fully described and illustrated the practice of the present invention, what I desire to claim is:

1. In a process for producing diolefins comprising the steps of passing an olefin-containing hydrocarbon feed stock through a dehydrogenation zone maintained under conditions to convert olefin to diolefin and in which product is removed from the dehydrogenation zone and passed to a quenching zone, the step of cooling the product in the quenching zone to a temperature substantially above atmospheric by bringing it into intimate contact with a mineral oil containing free oxygen and having an oxidation inhibitor added thereto.

2. In a process for producing diolefins including the steps of passing an olefin-containing hydrocarbon feed stock into a dehydrogenation zone and maintaining it in said zone under conditions to cause the production of diolefin and acetylene, removing product from the dehydrogenation

zone to a quenching zone, removing product from the quenching zone, further cooling to condense at least a portion of the product, separating the condensed product and passing the uncondensed product into an absorption zone, the steps of contacting the product in the quenching zone with a mineral oil containing free oxygen and having an oxidation inhibitor present therein to cool said product to a temperature substantially above atmospheric and the step of contacting the uncondensed hydrocarbons in the absorption zone with a mineral oil having an oxidation inhibitor added thereto.

3. In a process for producing diolefins from a hydrocarbon feed stock comprising olefins by passing the feed stock through a dehydrogenation zone to convert at least a portion of the feed stock into diolefin and acetylene, passing the product from the dehydrogenation zone into a quenching zone to reduce its temperature to a temperature substantially above atmospheric, removing hydrocarbon vapors from the quenching zone, cooling said vapors to condense a portion thereof, separating the condensed portion from the uncondensed portion, and passing the uncondensed portion through an absorption zone, the steps of adding an oxidation inhibitor to a heavy hydrocarbon oil containing free oxygen and employing the oil containing the inhibitor as the quenching oil in the quenching zone and as the absorption oil in the absorption zone.

4. A method in accordance with claim 3 in which the inhibitor is a phenol of petroleum origin.

5. A method in accordance with claim 3 in

10

which the heavy hydrocarbon oil is a naphthenic gas oil and in which the oxidation inhibitor is a phenol of petroleum origin.

6. A method in accordance with claim 3 in

5 which the heavy hydrocarbon oil is a petroleum raffinate and in which the oxidation inhibitor is a phenol of petroleum origin.
